UNITED STATES PATENT OFFICE.

CHARLES L. KELLER, OF WYOMING, OHIO, ASSIGNOR TO THE RICHARDSON COMPANY, OF LOCKLAND, OHIO, A CORPORATION OF OHIO.

SHINGLE.

Application filed October 8, 1919. Serial No. 328,627.

To all whom it may concern:

Be it known that I, CHARLES L. KELLER, a citizen of the United States, and a resident of the town of Wyoming, in the county 5 of Hamilton and State of Ohio, have invented certain new and useful Improvements, in Shingles, of which the following is a full, clear, and exact description, reference being had to the drawings forming 10 part of this specification.

My invention relates to shingle strips ordinarily made up of flexible composition material and to a strip shingle of novel shape produced by a novel process of cutting.

One of the objects of my invention is to provide a strip shingle which will give a panel or wide space effect when laid as distinguished from an ordinary shingle, and 20 another object is the formation of a shingle which can be laid with a variety of effects.

These objects and other advantages to be noted, I accomplish by that certain method 25 of cutting with the resulting novel strip shingles and roofing effects obtained thereby to be hereinafter more specifically pointed out and claimed.

In the drawings,

Figure 1 is a plan view showing a sheet 30 of roofing in which my novel shingles are blanked out.

Figure 2 is a like view showing another blank.

Figure 3 is a perspective view of a section 35 of a roof showing the use of my new strip shingle.

Figure 4 shows another form of roofing.

Figure 5 shows an additional blank.

By reference to the blanked out roofing 40 sheet, it will be noted that I form a series of strips 1 (Figure 1) forming roofing units, each of which is alike and has interspaced extensions 2, and spaces or depressions 3, on one edge of the strip and extensions 4 and depressions 5 along the opposite edge thereof.

The manner in which the completed strips will be used depends upon the position of the ends thereof, since the units must be 50 jointed at the spaces, and not at the projections, in courses on a roof. Thus if the strip is to be employed with narrower extensions than spaces, the cuts forming the ends of the units will be formed along the lines 6, while 55 if the extensions are to be wider than the spaces, the ends will be along the lines 7.

As many shingle-like extensions will be left between the ends of the units, as is desired for convenience in mounting, and it will be observed that the completed strips will be 60 used with the edge exposed that has its ends between the walls of a space or depression.

The roof shown in Figure 4 is made with the portions 2, 3, exposed and that of Figure 3 is made with the portions 4, 5, exposed. 65 Upon examination of the roof drawings it will be apparent that when the shingles produced by my method of cutting are laid, with the extensions of succeeding courses staggered, that the extensions of one 70 course will over-lie the meeting lines of the shingle sections or unit strips of the preceding course. It will also be apparent that considering any one strip, there is a back cut or depression 5 of equal size to every extension 2, that lies opposite or opposed to the extension, and the same way for the depressions, which are opposed by backward extensions.

The result of this last is that, the shingle 80 strips must be made wide enough so that the back cuts of each course will not become exposed by the space or depression in the next course to it, but that the backward extensions of each course are in line with the 85 back cuts of the preceding course thereby supplying extra material to the unexposed surface of the roof at the point that it is needed.

It will be readily apparent that the directions to the user in laying the strips resulting from this method of cutting will include instructions to employ the strips in such a way that the proper edge is exposed to view, in order to insure that the line of 90 division between the units or pieces of each course will be at a depression instead of at an extension.

It is also apparent that I obtain a strip shingle which will give paneled or wide 100 spaced effect to a roof with exposures of T-shape or inverted T-shape in a manner which produced all identical strips. So far as I am advised, this has been considered impossible in the past and further has been 105 considered entirely impractical in rectangular shaped shingles having a "back cut" and in strip shingles providing square or diamond shaped exposures.

The modification of my invention lies in 110 the provision of strips which are half provided with narrow extensions and half wide

extensions, unless, of course, the extensions and spaces are made of equal size, which is not preferred.

By reference to the blanks in Figures 2, 5 it will be noted that I form wide extensions 10 for the sections *a*, and narrower extensions 11 for the sections *b*, the former being interspaced by narrower depressions and the latter by wider depressions.

10 The back edges of the units have depressions 12 for the strips *a*, and the depressions 13, for the strips *b*, in such a way that the depressions of any one section are of the approximate width and lie directly opposed 15 to the extensions of the exposed edge, while the extensions between the back-cut depressions are of the approximate width of the depressions of the exposed edge. The depth of the back cuts or length of the extensions 20 is not so great as the length or depth of the cuts in the exposed edge, however, which results in the formation of rights and lefts or different sections *a* and *b*, as pointed out above.

25 The ends of the units *a* and *b*, as at 14, for the strips *a*, and 15 for the strips *b*, result in each strip having its exposed edge bisected through a depression and not an extension.

30 When so formed the separate pieces will be capable of being laid on a roof in a great variety of ways, since the extensions of each course will be bound to overlie the lines of separation between the shingle strips of the 35 succeeding course.

In another form of my invention, as shown in Figure 5, the units have a single projection for exposure, as would result when equidistant or equal parallel lines 15, 40 are cut through the material and the sections are made up into individual shingles by the cross cuts 16 (in the example shown). The roof laid with the individual shingles resulting from this cut will have the effect 45 of a raised tile in its appearance and the back cuts will effect a saving of material as in my other forms.

In all of the forms one essential is the fact that the back-cuts or unexposed cuts of the shingles or strips shingles are made 50 so that the depressions thereof will be co-axial with the extensions of the exposed edge. This essential may be varied somewhat, however, so long as the nature of the strips is not such as to bring the depressions of the back cut into any substantial alignment with the depressions of the exposed edge.

Having thus described my invention, what I claim as new and desire to secure by 60 Letters Patent, is:—

1. A roofing formed from shingle strips comprising body portions with the side edges as distinguished from the ends cut so as to form alternate extensions, and interlying spaces of a character to leave exposed a panel-like portion of roofing beneath, said extensions and spaces being formed so that the extensions are of different width from the spaces, and the one side edge of the strip having projections opposite the spaces on the other side edge and of equal size thereto, and said strips laid in overlapping courses so that the extensions are in staggered relation with each other. 70

2. A roofing formed from shingle strips comprising body portions with the side edges as distinguished from the ends cut so as to form alternate extensions, and interlying spaces of a character to leave exposed a panel-like portion of roofing beneath, said extensions and spaces being formed so that the extensions are of different width from the spaces, and the one side edge of the strip having projections opposite the spaces on the other side edge and of equal size thereto, and said strips laid in overlapping courses so that the extensions are in staggered relation with each other, and with the strips in any one course having the same side edges exposed, but with the strips in selected courses having different side edges exposed from other courses. 80

CHARLES L. KELLER.
